AMBROSE F. GEORGE AND FRANK RADEMACHER, OF LOS ANGELES,
CALIFORNIA.

REFRIGERATING MEANS.

SPECIFICATION forming part of Letters Patent No. 728,702, dated May 19, 1903.

Application filed December 30, 1901. Serial No. 87,810. (No model.)

To all whom it may concern:

Be it known that we, AMBROSE F. GEORGE and FRANK RADEMACHER, citizens of the United States, residing at Los Angeles, in the county of Los Angeles, State of California, have invented new and useful Improvements in Refrigerating Means, of which the following is a specification.

Our invention relates to means to preserve fruits, meats, and other perishable articles by keeping them in a low temperature for a long period of time, and thereby render it possible to transport these articles long distances.

Our invention is especially valuable as applied to railway-cars used in the transportation of fruits, meats, vegetables, and all perishable articles; but it is likewise adapted to be used in any situation where a refrigerant is required. A description of the same as applied to fruit-cars will explain the details of our invention, so that the same may be readily understood without detailing at length the different uses to which it may be applied and the manner in which it is applied.

Our invention will also be found especially valuable in connection with refrigerators in hotels, private residences, &c., which require to be frequently replenished with ice or other refrigerant to maintain therein a reduced temperature. We will, however, limit our description to the manner of applying our invention to a fruit-car, that any one versed in such matters may readily practice our invention.

In the accompanying drawings, forming part of this specification, are three figures, viz: Figure 1 is a vertical longitudinal section of a car embodying our invention. Fig. 2 is a vertical transverse section of said car, taken on the line 2-2 of Fig. 1 and looking in the direction indicated by the arrow on the drawing in proximity thereto. Fig. 3 is another vertical transverse section taken on line 3-3 of Fig. 1 and looking in the direction indicated by the arrow.

In the drawings, A represents the storing chamber or compartment in which the article to be transported is packed. This chamber is inclosed in the usual well-known casing for refrigerator-cars, composed of non-

conducting substances. At the top of this chamber and above the end of the car we place a brine or chlorid-of-calcium tank or receptacle B, which is filled with brine reduced in temperature to the proper degree and adapted to be transferred from one point to another through pipes.

In the lower part of the car and beneath the flooring of the storage-chamber we provide a drip-chamber C, which is connected with the brine-chamber by a series of refrigerating-pipes D. (We have shown six in number.) These pipes are disposed along and close to the ceiling of the storage-chamber, (being the zone of the warmest air in refrigerators,) commencing with the brine-chamber at the other end of the car. They are united by means of a series of T's F with the pipe E. On this pipe E is placed a thermostat G of suitable construction to regulate the size of the opening through the pipe by means of different degrees of temperature. As this thermostat is no part of our invention, we will not describe it, having shown it only in a general way. It is so arranged, however, that whenever the temperature in the chamber falls below 40° it will shut off connection between the brine-chamber and the drip-chamber C, and when the temperature rises above 40° it will open and permit the brine in the pipes D along the ceiling to pass gradually down into the drip-chamber. This will cause the cold brine to flow into the pipes from the brine-chamber and again reduce the temperature to or below 40°, when it will again close. By this means the brine in the chamber will be permitted to feed down into the drip-chamber as it is required to reduce the temperature in the storage-chamber and no faster, and it will maintain in the chamber of the car a uniform temperature while it lasts. The drip-chamber has a capacity at least equal to that of the brine-chamber, so that all the brine in the brine-chamber may work down into the drip-chamber through the thermostat. Below each refrigerating-pipe we place a drip-trough H, connected to the ceiling of the chamber by the supports I. This will prevent the moisture condensed on the refrigerating-pipes from dropping down into the storage-cham-

ber and damaging the contents therein. These drip-troughs are inclined in the direction of the drip-pipe J, with which they are all connected. This drip-pipe passes down to and forms an S-trap K, and thence passes out of the car. This trap enables us to maintain a liquid seal in the pipe to prevent the warm air on the outside of the car from entering into the storage-chamber. By this means all moisture generated in the car will be carried off, and the air therein will soon become thoroughly dry and be kept in that condition.

Leading from the end of the drip-tank at 15 the end next below the brine-tank is a vent-pipe L, which will permit the air in the drip-receptacle to pass up into the brine-tank as the brine passes from the brine-tank into the drip-tank. On this pipe we place a non-return valve M to prevent any brine from passing down the same into the drip-tank.

In the brine-tank we place a float-cover N to prevent the brine from spattering around while the car is in motion. The brine-tank 25 is filled with refrigerated brine by means of pipe connection with the screw-threaded opening O, the same being closed by the screw-plug P. This is housed by the pivoted cover Q, held closed by the hasp R.

Below the center of and connecting with the drip-tank we provide a discharge-port S, controlled by the valve T, which will normally keep the port closed; but when the pipe-coupling is placed in this port and proper connection made to drain off the contents of the drip-tank the valve-wheel V is turned, which will raise this valve T and permit the contents to pass out of the drip-tank through the port. When the contents are drawn out, 40 the valve-wheel is unscrewed, permitting the valve T to close, when the pipe connection is removed and the plug W is firmly screwed into the opening. Thus while the brine-tank is being filled with refrigerated brine the drip-tank is emptied of the warmer brine by 45 means of pipe connections and is refrigerated again for future use.

Having described our invention, what we claim as new, and desire to secure by Letters 50 Patent, is—

1. In a refrigerator, a storage-chamber; a brine-tank on the top thereof; a drip-tank below the same; refrigerator-pipes leading from the brine-tank through the storage-chamber, 55 and communicating with the drip-tank; an air-pipe extending from the drip to the brine-tank, a thermostat on the brine-conducting pipes leading from the brine-tank to the drip-tank; and means to connect the brine-tank with a refrigerated brine-supply tank and means to connect the drip-tank with a receiving-tank for warm brine, whereby the

contents of the drip-tank may be transferred from the drip-tank and refrigerated for future use.

2. The herein-described means for maintaining a uniform temperature in a storage-chamber, comprising a brine-tank having detachable valvular connections adapted to be connected with a refrigerator storage-reservoir; a storage-chamber below said brine-tank, a drip-tank below the storage-chamber, the said drip-tank being connected with the brine-tank by brine-conveying pipes extending through the storage-chamber; a thermostat in the chamber on the brine-connecting pipes to regulate the flow of brine from the brine to the drip tank, the brine-tank having air connections with the drip-tank to permit the passage of air from the drip to the brine tank, the brine-tank being provided with valvular means to detachably connect with a stationary reservoir for discharging the warmer brine from the drip-tank, whereby new and refrigerated brine may be supplied to the brine-tank and the warmer brine removed from the drip-tank without affecting the temperature in the storage-chamber, while the storage-chamber may be moved from place to place.

3. The herein-described means for transporting perishable articles long distances, comprising a railway-car provided with a storage-chamber for the reception of said articles; a brine-tank above the same and a drip-tank below the storage-chamber, connecting-pipes extending from the brine-chamber through the storage-chamber to the drip-tank for conveying brine, thermal means in the storage-chamber on the connecting-pipes to regulate the flow of brine from the upper to the lower tank; a vent-pipe extending from the drip to the brine tank to permit the passage of air only from the drip to the brine tank, the upper tank being provided with means to connect with a stationary reservoir for supplying refrigerated brine, the lower tank being provided with means to detachably connect with a stationary brine-receiving reservoir, whereby the warm brine may be drawn off from the drip-tank while the brine-tank may be supplied with a new supply of refrigerated brine, in a short space of time and not affect the temperature in the storage-chamber.

In witness that we claim the foregoing we have hereunto subscribed our names this 24th day of December, 1901.

AMBROSE F. GEORGE.
FRANK RADEMACHER.
